UNITED STATES PATENT OFFICE.

CHARLES B. ROGERS, OF JOPLIN, MISSOURI.

PULLEY.

Application filed March 12, 1925. Serial No. 15,127.

This invention relates to pulleys, and more particularly to a pulley adapted for use in connection with the lower end of an elevator belt.

5 In concentrating plants where crushed rock must be raised for gravity treatment, the elevator belts and pulleys are subjected to considerable wear due to the fact that the water and crushed material, which is spilled 10 by the elevator buckets, finds its way between the lower pulley and the belt and has an abrasive action thereon. The lower pulley operates in a pit submerged or partially submerged in water and crushed material finds 15 its way between the belt and pulley.

While the pulley forming the subject matter of the present invention is not necessarily restricted in use to the lower pulleys of elevator constructions, it is particularly adapted 20 for this purpose and designed to reduce to a minimum the lodgement of crushed material between the belt and pulley and thus lessen the wear on the belt.

An object of the invention is the provision 25 of a pulley that will effectually guide the lower end of the elevator belt with the least friction compatible with operation.

A further object is the provision of a pulley 30 in which the parts may be quickly and easily replaced, in case of injury or due to normal wear, without discarding the entire pulley.

A further object is the provision of a pulley 35 that can be cheaply manufactured and by reason of the uniformity of wearing, parts may be replaced and maintenance reduced to a minimum cost.

In the accompanying drawings, I have shown one embodiment of the invention. In this showing:

40 Figure 1 is a front elevation of the pulley,
Figure 2 is an end elevation,

Figure 3 is a fragmentary perspective view of a portion of the pulley, parts being shown in section, and,

45 Figure 4 is a perspective view of a portion of one of the pulley units.

Referring to the drawings, the reference numeral 1 designates a hub, one of which is employed at each end of the pulley, as shown 50 in Figure 1 of the drawings. These hubs are provided with flanges 2 having apertures for the reception of bolts 3, which pass through similar apertures formed in a flange 4 arranged on the end of a gudgeon 5. As shown, 55 the gudgeons extend outwardly to form a bearing shaft for the pulley. The hubs may

be mounted on a continuous shaft, if desired, as the mounting of the hub forms no part of the invention.

A plate or disk 6 is carried by each of the 60 hubs and radial arms 7 are secured to these disks by means of bolts 8. As shown, the radial arms are substantially U-shaped and are provided with peripheral members 9 which form the periphery of the pulley. The 65 arms are preferably formed of steel or similar material. A protecting cast iron plate 10 is bolted to each of the arms, as at 11, and these plates are provided with side flanges 12 which are arranged on the sides of the arms 70 (see Figure 3) to protect them. The body portion of the protecting plate extends upwardly beyond the flanges, as indicated at 13. A shoe 14 is secured to the peripheral portion 75 9 of the radial arm and is provided with side flanges 15. As shown, the projecting portion 13 of the side protecting plate extends between the flanges of the shoes. The shoe is secured to the arm 9 by means of bolts 16 which, as shown, are received in counter-sunk openings 80 17 to give a smooth upper surface. As shown, in Figure 4 of the drawings, the shoe may be slightly elevated at its longitudinal center, the point where the belt centers in operation.

The operation of the device will be apparent 85 from the foregoing description. By providing the plurality of units, a skeleton pulley is formed which materially reduces the possibility of crushed rock and water lodging between the belt and the pulley and thus causing 90 undue wear. It will be apparent that any part of one of the units may be readily and quickly replaced, and that when the shoes become worn in normal use, they may be 95 readily replaced.

It is to be understood that the form of my invention herewith shown and described is to be taken as a preferred example of the same, and that various changes in the shape, size, and arrangement of parts may be resorted to 100 without departing from the spirit of the invention or the scope of the subjoined claims.

I claim:

1. In a device of the character described, a pair of spaced coaxial hub plates, a plurality 105 of circumferentially spaced U-shaped members arranged between said plates, said members having their base portions arranged outwardly of said plates and their arms extending inwardly radially with respect to said plates and secured thereto, reinforcing members carried by the arms of said U-shaped

members between the outer edges of said plates and the outer ends of said arms, and relatively heavy shoes secured against the outer faces of the base portions of said U-shaped members and extending substantially throughout the length thereof.

2. In a device of the character described, a pair of spaced coaxial hub plates, a plurality of circumferentially spaced U-shaped members arranged between said plates, said members having their base portions arranged outwardly of said plates and their arms extending inwardly radially with respect to said plates and secured thereto, reinforcing members carried by the arms of said U-shaped members between the outer edges of said plates, and the outer ends of said arms, each of said reinforcing members being provided with flanges embracing the edges of the arms of said U-shaped members, and relatively heavy shoes secured against the outer faces of the base portions of said U-shaped members and extending substantially throughout the length thereof.

3. In a device of the character described, a 25 pair of spaced coaxial hub plates, a plurality of circumferentially spaced U-shaped members arranged between said plates, said members having their base portions arranged outwardly of said plates and their arms extending 30 inwardly radially with respect to said plates and secured thereto, reinforcing members carried by the arms of said U-shaped members between the outer edges of said plates, and the outer ends of said arms, each 35 of said reinforcing members being provided with flanges embracing the edges of the arms of said U-shaped members, and relatively heavy shoes secured against the outer faces 40 of the base portions of said U-shaped members and extending substantially throughout the length thereof, each of said shoes being provided in its inner face with a longitudinal groove receiving the base portion of the 45 corresponding U-shaped member.

In testimony whereof, I affix my signature.

CHARLES B. ROGERS.
